(57) **CLAIM**

The ornamental design for a mechanical oscillatory stimulation therapy device, as shown and described.

DESCRIPTION

FIG. 1 is a top perspective view of a mechanical oscillatory stimulation therapy device showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The broken lines shown in the drawings are for the purpose of illustrating portions of the mechanical oscillatory stimulation therapy device, which form no part of the claimed design.
